VENDING MACHINE

Harry F. Mayfield, Anderson, S. C.

Application June 2, 1938, Serial No. 211,437

8 Claims. (Cl. 312—37)

My invention is a machine for vending or dispensing articles having grommets, such as towels.

An important object of the invention is to provide a machine of the above mentioned character which will accurately vend only one grommet carried article at a time, and render it impossible for more than one article to be vended, during one operation of the machine.

10 A further object of the invention is to provide a machine of the above mentioned character which is relatively simple in construction and reliable in operation.

15 A further object of the invention is to provide a rod or the like for supporting a number of the grommets, with means carried by the rod for controlling the discharge of the grommets from the rod.

20 A further object of the invention is to provide means for removably supporting one end of the grommet carrying rod so that the rod may be readily loaded with the grommets.

25 Other objects and advantages of the invention will be apparent during the course of the following description.

In the accompanying drawings forming a part of this application and in which like numerals are employed to designate like parts throughout the same,

30 Figure 1 is a perspective view of a vending machine embodying my invention.

Figure 2 is a vertical section taken on line 2—2 of Figure 1.

35 Figure 3 is a plan view of the grommet carrying rod and operating means.

Figure 4 is a transverse section taken on line 4—4 of Figure 3.

Figure 5 is a vertical section taken on line 5—5 of Figure 3.

40 Figure 6 is a longitudinal section taken on line 6—6 of Figure 3.

Figure 7 is an enlarged side elevation of the grommet carrying rod, parts in vertical section and parts in elevation.

45 Figure 8 is a vertical section taken on line 8—8 of Figure 7.

Figure 9 is a transverse section taken on line 9—9 of Figure 6.

Figure 10 is a perspective view of a grommet carrying rod and associated elements, and,

50 Figure 5a is a perspective view of one end of a link, parts broken away.

In the drawings, wherein for the purpose of illustration is shown a preferred embodiment of

55 my invention, the numeral 15 designates a ver-

tical casing, having a front door 16, to afford access to the interior of the casing, and hinged at 17. This door may be held in the closed position by a lock 18 or the like. The door 16 is provided in its upper portion with an opening or window 19, through which the individual towel is passed, when vended, and a lower opening 20, through which the used towel may be returned into the lower portion of the casing.

A generally horizontal frame 21 is supported within the upper portion of the casing 15, and the operating parts of the vending mechanism are carried by this horizontal frame. Arranged upon the frame 21 and rigidly secured thereto is a horizontal block 22, having an inclined opening 23, for removably receiving a grommet carrying element or rod 24, adapted to be clamped within the opening 23 by a set screw 25. The rod or element 24 is inclined and extends downwardly toward its free end. The rod 24 is arranged transversely within the casing 15 and its forward or free end is disposed inwardly of and preferably opposite the opening 19. The rod 24 is therefore rigidly supported, in use, and is provided at its forward end with a loop 26, having

20 connection with a chain or flexible element 27, extending outwardly through the opening 19 and then inwardly through the opening 20 and attached to the bottom of the casing 16, as shown at 28. There is sufficient slack in this chain or

25 flexible element to permit of the proper use of the towel before it is returned into the casing, through the opening 20. The element or rod 24 has a longitudinal groove or opening 29, for receiving a reciprocatory bar or rack bar 30, having recesses 31 formed therein, receiving transverse guides 32, rigidly secured to the rod 24, by solder or the like. These guides limit the longitudinal movement of the bar or rack bar 30 in

30 opposite directions. The bar 30 is provided at 35 its rear end with a lateral extension or head 32', carrying a pin 33, arranged to one side of a pin 34, rigidly attached to the rear end of the rod 24. A compressible coil spring 35 surrounds the pins 33 and 34 and shifts the bar 30 to the extreme rear or retracted position. At its forward

40 end, the rod 24 has a vertical opening 36, formed therein, within which is mounted a vertical dispensing element, in the form of a wheel or gear 37, rotatably mounted upon a horizontal transverse pin 38, attached to the rod 24. This wheel or gear 37 has a portion of its periphery provided

45 with teeth 39, in permanent mesh with teeth 40, formed upon the forward end of the bar 30. The wheel or gear 37 has the upper portion of its

50 55 55

periphery formed plain and is provided with a notch 39'.

The rod 24 slidably receives thereon grommets 41, suitably attached to towels 42 or like articles 5 to be vended. These grommets are of such a thickness or size that only one of them can enter the notch 39' when the wheel or gear 37 is turned clockwise, Figure 7, to the end of its movement, and when the wheel or gear 37 is turned counter-clockwise, Figures 6 and 7, the leading grommet within the notch 39' is fed forwardly upon the rod 24, and will be free to pass out of the forward end of the notch 39'. When the wheel or gear 37 moves from the end of its clockwise or 15 loading position, it prevents the discharge of the grommet next to the leading grommet, since it projects radially beyond the rod 24.

Means are provided to move the bar 30 forwardly, to discharge or release the leading grommet, comprising a horizontal lever 41', pivotally supported at one end, as shown at 42'. The free end of this lever is forked, as shown at 43, to receive therebetween the rear end of a link 44. A pin 45 is rigidly attached to the lever 41' and 25 has one end extending into a slot 46 in the link 44 while its upper end projects beyond the lever 41' and has connection with a retractile coil spring 47, attached to a pin 48, rigidly secured to the link 44. The numeral 49 designates a 30 stationary stop to limit the rearward movement of the link 44. When the link 44 is moved forwardly, in the direction of its arrow, it pulls the lever 41' forwardly, through the medium of the spring 47, which is stiffer than the spring 35. 35 The forward end of the link 44 is slidably supported in a guide 50, arranged beneath and rigidly secured to a horizontally swinging operating lever 51, pivotally supported at one end at 52. This operating lever has an extension 53, extending 40 to the exterior of the machine, and slidable in a guide 54. The operating lever is shifted to the rear or starting position by a retractile coil spring 55, secured thereto by a pin 56, and secured at its rear end to a stationary pin 57. The 45 lever 51 is provided with a transverse group of ratchet teeth 58, to be engaged by a pivoted dog 59, the arrangement being such that the teeth 58 will trip over the dog 59 when the lever 51 is swung forwardly. The lever will therefore be 50 held against returning movement after it has been shifted part way from its rear position, but when the lever has been shifted to the extreme forward position, the group of ratchet teeth 58 will clear the dog 59, and when the lever is then 55 released, the dog 59 will swing freely rearwardly upon its pivot, so that spring 55 can return the lever 51 to its rearmost position.

Arranged upon one side of the link 44 is a laterally swinging shifting lever 60, pivotally supported at its rear end at 61, and this lever has an angularly arranged extension 62 at its free end. This extension is disposed in the path of travel of the pin 56. The lever 60 has a transverse strap 63, rigidly secured thereto, as shown at 64, and this strap has a down-turned end 65, engaging the edge of the link 44.

The operating lever 51 has a coin receiving element or lug 66, provided with a vertical coin slot 67, also passing through the lower face of the lever 51. The lug 66 has an upwardly flaring recess 68, to receive the coin and conduct it to the slot 67. A stationary coin guide shute 69 is secured to the top of the casing 15, and has its lower end arranged over the recess 68, when 70 the lever 51 is in the rearmost position. The 75

link 44 has its forward end extending beneath and across the lever 51, Figure 5, and the link 44 is provided with a coin receiving pocket 70 and the link also carries a coin supporting lip 71, arranged beneath the same and rigidly attached thereto. The link 44 is swung to the left, Figure 3, to the limit of its movement by a retractile coil spring 72, and is swung to the right by the down-turned portion 65.

The grommets 41 are arranged upon the inclined rod 24, and gravitate downwardly upon the rod toward its free end, but are aided in this movement by a weight 73, supported by a roller 74, traveling upon the inclined rod 24. The weight is preferably provided upon its front side 15 with the designation "Empty" so that when the last towel is vended this signal will be given.

The operation of the machine is as follows:

With the parts arranged as shown in Figures 3 and 6, the wheel or gear 37 is projecting 20 radially beyond the rod 24, since the bar 30 is in the rearmost position. This wheel or element thereby positively prevents the leading grommet from passing off of the rod 24. The coin is inserted into the shute 69 and is conducted into 25 the coin slot 67 and enters the pocket 70 of the link 44 and is supported in the opening 70 by the lip or element 71, so that it cannot drop out of the slot 67. The lever 51 is now swung manually clockwise or forwardly, Figure 3, and this movement of the lever is transmitted to the link 44 through the medium of the coin, the link 44 now moving to the left, Figure 3. When the link 44 moves to the left, the lever 41' swings in the same direction, and this lever 41' acts upon the 30 head 32' and moves the bar 30 to the left. This movement of the bar 30 causes the wheel or gear 37 to turn from the normal position, Figure 6, clockwise to the position shown in Figure 7, so that the notch 39' assumes the rearmost position. The leading grommet 41 now enters the notch, but the next grommet cannot enter it. When the lever 51 is swung to the left, the pin 56 carried thereby, contacts with the angular extension 62, thereby swinging shifting lever 60 to 45 the right, causing strap 63 to shift the forward end of the link 44 laterally. This shifts the lip 71 from beneath the coin so that the coin may drop from within the slot 67. When this occurs, the link 44 is disconnected from the lever 51, and the spring 35 will shift the bar 30 rearwardly, which will turn the wheel or gear 37 counter-clockwise to the position shown in Figure 6, so that the notch 39' will free the grommet therein. The lever 51, when shifted to the end of its 50 forward movement, and released, will be returned to the rearmost position by the action of spring 55.

It is thus seen that manually operated means has been employed to move the lever 41', for shifting the bar 30 forwardly. The invention is in no 60 sense restricted to the use of manual means for this purpose, as any suitable means, electrical or otherwise, may be used to shift the bar 30 forwardly. This means may or may not be coin 65 controlled.

It is to be understood that the form of my invention herewith shown and described is to be taken as a preferred example of the same and that various changes in the shape, size and arrangement of parts may be resorted to, without departing from the spirit of my invention or the scope of the subjoined claims.

Having thus described my invention, I claim:

1. In a machine for vending towels or the like

having grommets, a rod to receive the grommets thereon, a wheel pivotally mounted upon the rod and extending radially therebeyond and having a notch to receive each of the grommets in succession and also having gear teeth, a bar extending longitudinally of the rod and having gear teeth engaging the gear teeth of the wheel, and means to move the rod longitudinally.

2. In a machine for vending towels or the like having grommets, a rod to receive the grommets thereon, a wheel mounted upon the rod extending radially beyond the same and having a notch to receive each of the grommets in succession and also having gear teeth, a reciprocatory bar extending longitudinally of the rod and having gear teeth to engage the first named gear teeth, a spring to move the bar in one direction, and means to move the bar in an opposite direction.

3. In a machine for vending towels or the like having grommets, a rod to receive the grommets thereon and having a transverse opening and a longitudinal groove, a wheel pivotally mounted within the transverse opening and extending radially beyond the rod and having a notch to receive each of the grommets in succession and having gear teeth, a reciprocatory bar mounted within the longitudinal groove and having gear teeth to engage the first named gear teeth, means to limit the longitudinal movement of the bar, a spring to move the bar in one direction, and means to move the bar in an opposite direction.

4. In a machine for vending towels or the like having grommets, a rod to receive the grommets thereon, an element having means to control the passage of grommets longitudinally of the rod and having gear teeth, means to pivotally support said element and retain the same adjacent to the rod, a bar slidably engaging and extending longitudinally of the rod and having gear teeth engaging the first named gear teeth, and means to move the bar longitudinally.

5. In a machine for vending towels or the like having grommets, a rod to receive the grommets thereon, an element having means for controlling the passage of the grommets longitudinally of the rod and having gear teeth, means to pivotally

mount the element upon the rod, a bar extending longitudinally of the rod and having gear teeth to engage the first named gear teeth, and means to move the bar longitudinally.

6. In a machine for vending towels or the like having grommets, a rod to receive the grommets thereon and having a longitudinal groove, a pivoted element having means controlling the passage of the grommets longitudinally of the rod, said means including a part adapted to extend radially beyond the rod, and means to pivotally support said element and retain the same adjacent to said rod, and means including a rack and pinion to turn the pivoted element, said rack being arranged within the longitudinal groove. 15

7. In a machine for vending towels or the like having grommets, a rod to receive the grommets thereon, said rod being provided near its free end with a recess, said rod also having a longitudinally extending passage, an element mounted within the recess having means for controlling the movement of grommets from the rod, said means including a part adapted to project radially beyond the rod, gear teeth connected with the element, a bar mounted to move longitudinally within the passage and held thereby against turning movement upon its longitudinal axis, said bar having gear teeth to engage the first named gear teeth, and means to move the bar longitudinally. 20 25

8. In a machine for vending towels or the like having grommets, a relatively stationary rod to receive the grommets thereon, an element having means for controlling the passage of the grommets longitudinally of the rod, means for mounting the element upon the relatively stationary rod and holding it against bodily movement longitudinally of the rod and permitting the same to move transversely of the rod, means to move the element transversely of the rod for releasing 40 each of the grommets in succession including a reciprocatory bar movable longitudinally of the rod, and means to hold the bar against turning movement upon its longitudinal axis and to reciprocate the same. 45

HARRY F. MAYFIELD.
